UNITED STATES PATENT OFFICE.

ARNOLD LUTSCHG, OF GREAT BEND, KANSAS.

MAIL-CARRIER-DISCHARGING GUN.

1,307,783.

Specification of Letters Patent.

Patented June 24, 1919.

Application filed November 27, 1918. Serial No. 264,431.

To all whom it may concern:

Be it known that I, ARNOLD LUTSCHG, a citizen of the United States, residing at Great Bend, in the county of Barton, State of Kansas, have invented a new and useful Mail-Carrier-Discharging Gun; and I do hereby declare the following to be a full, clear, and exact description of the invention, such as will enable others skilled in the art

10 to which it appertains to make and use the same.

This invention relates to the art of mail carriers for rural routes, for carrying the mail from the road-way to the house, and 15 more particularly to an improved mail carrier discharging gun, one to be located at the road-way and another at the house on the porch or other suitable location for discharging the carrier in either direction, that 20 is from either end of track-wire or trolley.

One of the objects of the invention is to provide a housed frame having guide tracks, and a spring tensioned carriage mounted on the guide tracks and a holding latch for 25 holding the carriage while under tension of its spring, whereby as the holding latch is released, the carriage is actuated by a spring, for discharging the carrier from under the housing either toward the house or toward 30 the road-way, along which the mail man passes.

A further object of the invention is to provide a device of this kind, for sending the mail either to the road-way or to the 35 house, thereby preventing the mail man from tramping from the road-way to the house or the occupants from the house to the road-way, when delivering or sending mail matter.

40 A further object of the invention is to provide improved means for connecting a member of the mail carrier to the holding latch.

A further object of the invention is to provide an improved mail carrier receiving 45 carriage, which is under spring tension, for discharging the mail carrier.

50 A further object of the invention is the provision of cushioning means at the forward ends of the guide tracks of the housed frame, for cushioning the carriage, thereby relieving the jar or the force of the blow incident to the discharge or release of the carriage.

In practical fields the details of construc-

tion may necessitate alterations falling 55 within the scope of what is claimed.

The invention comprises further features and combination of parts as hereinafter set forth shown in the drawings and claimed.

In the drawings:—

Figure 1 is a vertical sectional view through the mail carrier discharging gun, showing parts thereof in elevation.

Fig. 2 is a longitudinal sectional view on line 2—2 of Fig. 1, showing various parts in 65 plan.

Fig. 3 is an enlarged detail perspective view of portions of the parallel guide tracks of the housed frame, and the improved carrier discharging carriage mounted on the 70 tracks.

Fig. 4 is an enlarged detail perspective view of the forward end of one of the guide tracks, showing the cushioning bumper for the carriage.

Fig. 5 is a sectional view on line 5—5 of Fig. 4.

Referring more especially to the drawings, 1 and 2 designate forward and rear supports, which are provided with laterally 80 and downwardly inclined legs 3, the feet of which are designed to be fastened to suitable anchoring means, adjacent the road-way gate of the farm, or on the porch of the house back from the road-way. The upper 85 parts of the supports 1 and 2 are provided with laterally and partially upward curved arms 4, for the support of the housed frame. Side tracks 5 and 6 are provided and which are in parallelism. The side tracks each 90 comprises the upper and lower T rails 7 and 8, which are spaced, whereby the legs of the T's face each other, there being metal loop straps 9 straddling the rails sidewise, and having their ends secured at 10 to the upper 95 and lower faces of the upper and lower rails, thereby holding the rails spaced. The ends of the arms 4 of the supports are secured in any suitable manner to the forward and rear metallic looped straps 9, thereby firmly supporting the guide tracks in parallelism as shown in Fig. 2. These metallic looped straps are provided with outwardly extending ears 11, on which the elongated frame bars 12 rest. A suitable housing constructed 100 of any suitable thin sheet metal is provided. This housing 13 is arch shaped, and the lower portions of the side walls thereof have

60

90

95

100

105

outwardly extending longitudinally disposed flanges 14, which rest upon the frame bars 12, there being suitable means such as rivets or the like 15 passing through the 5 flanges 14 and through the bars 12 and the ears 11, thereby insuring a rigid structure or framing and reinforcing the housing. In order to additionally strengthen or reinforce the arch shaped housing, suitable arch 10 shaped straps 16 are riveted or otherwise secured at 17 to the inner face of the housing, as shown clearly in Figs. 1, 2 and 3. The lower side portions of the braces 16 are provided with laterally extending lugs 18, 15 which, by means of rivets 19, are secured to the frame bars 12, as shown clearly in Fig. 3, said rivets 19 also passing through the elongated flanges 14.

A carrier receiving and discharging carriage 20 is provided. This carriage is likewise arch shaped, comprising the arched bars 21, which are spaced apart as shown, and to which a suitable thin sheet metal housing 22 is secured in any suitable manner, as shown 25 in Fig. 1, said housing 22 in Fig. 2 is broken away, in order to show the structure there below. The lower side portions of the arched bars 21 of the carriage 20 are provided with laterally extending reduced stems or pintles 30 23, which extend between the spaced T's of the upper and lower rails of the guide tracks, there being anti-frictional rollers 24 journaled upon said stems or pintles, and designed to engage between the lateral flanges 35 of the upper and lower rails. Suitable cotter pins 25 pass through the extremities of the stems or pintles, to hold the outermost anti-frictional rollers or wheels on the stems, thereby consequently holding the stems between 40 the rails and the other anti-frictional wheels in place. The lower portions of the foremost arched brace of the carriage are provided with arms 26, the forward extending lugs 27 of which engage between the T's 45 of the upper and lower rails, thereby constituting bumpers, as will hereinafter appear. Extending from and integrally connected to the inner faces of the sides of the arched braces 21 of the carriage are upwardly and 50 inwardly protruding arms 28, to the inner downward extending extremities of which, a U-shaped carrier receiving frame 29 is integrally connected. The crotch or transverse portion 30 of this frame 29 is engaged by the 55 rear or butt end of the carrier 31, that is when the carriage is in position for discharging the carrier. The carrier may be any suitable construction, and made of sheet metal or of any configuration, and is provided with 60 a hinged door or closure 32, there being suitable locking means 33 for holding the door closed, that is after inserting the mail matter. The top of the carrier is provided with suitable brackets 34 in bearings of 65 lateral portions of which, suitable trolley

wheels 35 are journaled, so as to engage and ride on trolley wire 36. This trolley wire is designed to extend from the farm gate adjacent the road-way to the front porch or other suitable location of the farm house. 70 In this case the mail carrier discharging gun is at each end of the trolley wire. By means of the braces 37 and 38 (which are connected to the frame bars as at 39), a pair of parallel bars 40 is supported intermediate the sides of the housing 13. These bars 40 are integrally connected by the transverse piece 41 which is provided with an eye 42. Secured between the rear ends of the bars 40 is an upright plate 42', in 75 which a screw 43 is loosely mounted. A clevis member 44 is swivelly connected to the inner end of the screw 43, and to the clevis member one end of the trolley wire is connected as at 45. A thumb nut 46 is 80 threaded to the screw, and it is obvious that by adjusting the thumb nut the trolley wire may be tightened, to insure the proper tension. It is also to be noted that the trolley wire passes under the transverse portions 85 of the arched straps or braces 21 of the carriage, whereby the carrier may enter the carriage as shown in Fig. 1. Pivoted on a transverse pin 47, which is mounted in the opposite parallel bars 40, is a latch or trigger 48, between which and the eye 42 a spring 49 is connected, thereby holding the latch set against the transverse stop pin 50. A loop member 51 is carried by the forward 90 brace of the carriage, and extends rearwardly beyond the carriage, there being a transverse bar 52 connecting the opposite sides of the U-shaped member 51. This transverse bar 52 braces the U-shaped member 51, and is spaced from the rear transverse portion of the loop 51, to provide an 95 opening, for the reception of the latch or trigger, so as to hold the carriage set against the action of the spring 53, which connects between the carriage, that is its forward 100 brace 21, and an eye 54 of the transverse brace 55 of the foremost arch brace 16 of the housing 13. It is obvious that the spring 49 is of greater tension than the spring 53, and owing to the leverage action of the 105 trigger or latch, the trigger will hold the carriage in the position shown in Fig. 1 against the action of the spring 53. However, by actuating the trigger or latch, the rear portion of the loop 51 will be released, and through the action of the spring 53, the 110 carriage will be moved forwardly with sufficient force, to impart momentum sufficiently to the carrier, as to send it from the farm gate near the road-way to the farm 115 house, and vice-versa. In order to actuate the trigger or latch a lever 56 is pivoted on a transverse pin 57, which is carried by the bars 40, adjacent one of the bars, and is 120 provided at its lower end with a lateral arm 125 130

58. This lateral arm 58 extends across the forward edge of the lower end of the trigger or latch, whereby as pressure is applied to the lever 56 at its upper end in the direction of the arrow α , the trigger or latch will be oscillated against the tension of the spring 49, so as to release the loop 51 of the carriage. Pivoted to a depending arm 59 of one of the bars 40 is an angular lever 60, and it is to be observed that the arm 61 of said lever is formed into a loop, the arm 62 of which is pivoted at 63 to a depending arm 64 of the opposite bar 40. It is to be observed that the pivot 63 is axially opposite the pivot of the lever. The loop of the arm 61 straddles the two bars 40, and the loop end thereof is provided with a lug 65. It is to be noted that when the carriage is released and allowed to suddenly spring forward under the action of the spring 53, the transverse bar 52 will assume a position a short distance to the rear of the lug or projection 65. Therefore it is obvious that to reset the carriage against the action of the spring 53, the lever 60 may be oscillated, causing the projection or lug 65 to engage the transverse bar 52 and move the loop with its carriage rearwardly, sufficiently until the latch or trigger may be placed in engagement with the loop end of the member 51. Mounted between the upper and lower rails of the tracks are buffer members 66, which are provided with rubber bumpers 67. The buffer members 66 have connected thereto stems or rods 68, the rear ends of which are guided in openings 69 of the rear upright connections 70 between the upper and lower rails of the tracks. It is to be observed that the legs of the T rails are cut away a short distance to the rear of the upright connections 70, and secured to the stems or rods 68 by the pins 71 are collars 72. Interposed between the collars 72 and the rear uprights 70, and surrounding the stems or rods are coil springs 73, thereby holding the collars against the rear ends of the legs of the T rails. It is clear that when the carriage is released and allowed to move forwardly under the action of the spring 53, the impact will be so great against a stationary abutment, that the entire frame of the machine will be considerably jarred, and constant strains of this kind would, in a short while lessen the rigidity of the structure. Therefore, by the provision of the cushioning means comprising the buffers and the bumpers 67 against which the bumpers 27 contact, the jar incident to the release of the carriage is reduced to a minimum thereby extending the life of the structure. Suitable braces 74 connect between the supports 1 and 2, and certain of the intermediate metallic looped straps 9. Suitable brace rods 75 connect between the crotch of the arms 4 of the support 1, and the legs 3 of

the support 2. Similar tie rods 76 connect between the crotch of the arms 4 of the support 2 and the legs of the support 1.

The invention having been set forth what is claimed as new and useful is:—

1. In a mail carrier discharging gun, the combination with a supporting frame provided with parallel side guide tracks, of a carriage on said guide tracks, spring tensioning means therefor, a trolley wire, a carrier thereon and adapted to be received in said carriage, holding means to hold the carriage set against the action of its tensioning means.

2. In a mail carrier discharging gun, the combination with a supporting frame provided with parallel side guide tracks, of a carriage on said guide tracks, spring tensioning means therefor, a trolley wire, a carrier thereon and adapted to be received in said carriage, holding means to hold the carriage set against the action of its tensioning means, means to actuate the holding means to release the carriage.

3. In a mail carrier discharging gun, the combination with a supporting frame provided with parallel side guide tracks, of a carriage on said guide tracks, spring tensioning means therefor, a trolley wire, a carrier thereon and adapted to be received in said carriage, holding means to hold the carriage set against the action of its tensioning means, means to actuate the holding means to release the carriage, and means for resetting a member of the carriage in engagement with the holding means.

4. In a mail carrier discharging gun, the combination with a frame provided with side guide tracks, of a trolley wire connected to the frame, a mail carrier on said wire, a spring tensioned carriage on the tracks to receive the carrier whereby it may be discharged, said carriage having a rearwardly extending loop member, a spring tensioned device to engage the loop member to hold the carriage set against the action of its spring tensioning means, and a pivoted lever for actuating said device to release the loop.

5. In a mail carrier discharging gun, the combination with a frame provided with side guide tracks, of a trolley wire connected to the frame, a mail carrier on said wire, a spring tensioned carriage on the tracks to receive the carrier whereby it may be discharged, said carriage having a rearwardly extending loop member, a spring tensioned device to engage the loop member to hold the carriage set against the action of its spring tensioning means, and a pivoted lever for actuating said device to release the loop, and cushioning means carried by the tracks for the carriage, for taking up the impact of the blow of the carriage.

6. In a mail carrier discharging gun, the

combination with a frame provided with side guide tracks, of a trolley wire connected to the frame, a spring tensioned trigger on said frame, a carriage on the guide track 5 and provided with means to engage said trigger, spring means for the carriage, a carrier on the trolley wire to be received in said carriage, and a device to engage a part of the first means, whereby said first means 10 may be placed in engagement with the trigger.

7. In a mail carrier discharging gun, the combination with a frame provided with side guide tracks, of a trolley wire connected to the frame, a spring tensioned trigger on said frame, a carriage on the guide track and provided with means to engage said trigger, spring means for the carriage, a carrier on the trolley wire to be received in said carriage, and a device to engage a part of the first means, whereby said first means may be placed in engagement with the trigger, a device to actuate said trigger for releasing said means, and cushioning 20 means to absorb the impact of the blow of the carriage subsequently to its release.

8. In a mail carrier discharging gun, the

combination with a frame, of side parallel guide tracks on said frame, said tracks comprising upper and lower spaced T-rails, 30 means for holding the rails spaced, a housing connected to said means and arching from one side track to the opposite one, a trolley wire connected to the frame, a carriage on the guide track, a carrier on the 35 trolley wire to be received in said carriage, a loop extending rearwardly from the carriage, spring tensioned holding means to be engaged by the loop, spring means for the carriage, against which the holding means holds the carriage set, a lever to actuate the holding means to release the loop, cushioning means for the carriage to absorb the impact of the blow thereof incident to the release, and a lever to engage a part of the loop 40 for resetting the same in engagement with the holding means.

In testimony whereof I have signed my name to this specification in the presence of two subscribing witnesses.
